Primary Examiner — Richard E Chilcot(74) *Attorney, Agent, or Firm* — Juan Carlos A. Marquez; Marquez IP Law Office, PLLC(57) **CLAIM**

The ornamental design for an UVC LED sterilizing mummy bag, as shown and described.

DESCRIPTION

FIG. 1 is a perspective view of an UVC LED sterilizing mummy bag, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

1 Claim, 6 Drawing Sheets(56)
